UNITED STATES PATENT OFFICE.

ROBERT SCHEANBLUM AND GRACE SCHEANBLUM, OF NEW YORK, N. Y.

HAIR CURLER.

Application filed May 19, 1923. Serial No. 640,002.

To all whom it may concern:

Be it known that we, ROBERT SCHEANBLUM and GRACE SCHEANBLUM, residing at New York city, in the county and State of 5 New York, have invented a certain new and useful Hair Curler, of which the following is a specification.

This invention is a hair curler intended for use in the curling of bobbed hair and 10 constructed in such manner as to well adapt it for this purpose.

Widely varying types of curlers have been devised for the curling of long hair, but, so far as we are aware, no curler has ever 15 been produced which has for its specific purpose the curling of bobbed hair. Bobbed hair has for some time been considerably in vogue, yet prior to the present invention the curlers which have been used to curl 20 bobbed hair are those which have been commonly employed to curl long hair and are for the purpose of curling bobbed hair purely of a makeshift character and are not either especially adapted for this purpose 25 nor can they be conveniently employed to carry out this end.

It is of utmost importance in the curling of bobbed hair that the ends of the hair be properly curled and it is found in practice 30 that, prior to applicant's invention, not a single construction on the market was capable of properly catching and curling the ends of the hair for the reason that in every case the hair must be manually wrapped 35 around the curler while the curler is held stationary. During this wrapping operation, the ends slip free and are not properly caught with the result that while the greater portion of the length of the hair will be 40 properly curled the end portions will be straight thereby producing an unsightly and untidy appearance. For this reason, ladies prefer to employ curling irons when curling bobbed hair and curlers of the character 45 adapted to be worn overnight have not found favor with ladies having bobbed hair.

With the foregoing considerations in mind, the object of the present invention is to provide a curler of the type adapted to be 50 applied to the hair and left for a time, as overnight, and which shall be particularly intended for employment in the curling of bobbed hair. From a more specific standpoint, the present invention is a curler of 55 novel shape and of wire of such inherent

resiliency that the arms thereof shall normally stand divergent from the bend thereof but adapted to be brought in use into substantially parallel relation and which will tightly clamp the very ends of the hair 60 tightly together and to the curler in such manner that they cannot become loose, but will be, in contradistinction, as properly curled as is the rest of the hair.

In its preferred practical form, the invention consists in a curler constructed from braided cord spring wire, a suitable length of which is bent intermediate its ends to form two clamping jaws. Inasmuch as the wire is fairly pliable, these clamping jaws 70 may be readily bent, when desired, but are normally separated from one another except where they are joined together at their bases. They constitute two cooperating clamping jaws between which the ends of 75 the hair may be clamped and the curler thereupon rolled for the purpose of rolling it into the body of the hair and in this manner coiling the hair upon the curler until the curler is drawn up close to the 80 scalp. The curler is adapted for cooperation with a strand of hair somewhat less in width than the length of the clamping jaws, and in rolling the hair upon the curler, the hair is positioned at about the center of the 85 curler so that when it is rolled up portions of the curler will project beyond the opposite sides of the roll and these opposite sides are adapted to be bent over to further clamp the hair and preclude the roll from 90 loosening.

The construction is simple, economical, readily positioned on the hair and may be comfortably worn overnight.

Features of the invention, other than 95 those specified, will be apparent from the hereinafter detailed description and claim, when read in conjunction with the accompanying drawings.

The accompanying drawings illustrate 100 one practical embodiment of the invention, but the construction therein shown, is to be understood as illustrative, only, and not as defining the limits of the invention.

Figures 1, 2 and 3 show a hair curler in 105 the various steps of its assembly with a strand of bobbed hair; and,

Figure 4 is a view of the curler detached and in normal condition.

The curler of the present invention is 110

preferably made from wire, commonly referred to in the electrical arts as wire cord. This cord is so well known that it has not been considered necessary to show its structure in the drawings. It embodies a metal or wire core enclosed within an insulating envelope of rubber composition, exteriorly of which is positioned a woven or braided fabric envelope. The present invention is not directed to any novelty in the wire structure, but is particularly directed to a novel hair curler formed from such wire and the ends of which curler are provided with protecting means adapted to preclude the raveling or fraying of the fabric envelope or the withdrawal or retraction of the insulating envelope in such manner as would permit the ends of the wire to protrude with a tendency to cut or scratch the wearer.

Figure 4 of the drawings shows the curler of this invention. It is constructed from a suitable length of wire bent intermediate its ends as at 1 to form two arms 2 and 3, which are preferably of equal length and the free ends of which arms are protected in any suitable manner. In practice, we may provide metal tips or other metallic covering for these ends, but we find it economical and highly efficient to dip the ends into a plastic material, which, when the ends are withdrawn, form a globule on each end. These globules harden or set in a short time and form efficient protecting coverings on the ends of the curler. These protecting coverings are designated by the reference character 4 and while different plastic materials may be employed in their formation, sealing wax, shellac or other similar substance has been found thoroughly practical.

The normal condition of the curler is as shown in Figure 4 and from this view, it will be noted that the two arms 2 and 3 are not connected to one another except at the point 1, whereat they join. The arms moreover partake of the natural characteristics of the wire cord from which they are made and are thus more or less pliable and can be readily bent by manipulation between the fingers. As seen in Figure 4 the arms 2 and 3 normally extend from the bend or point 1 divergently and in use are brought into substantially parallel relation and in close contact with each other throughout the greater portion of their length, after the hair has been rolled thereupon, the protecting coverings 4 being of greater diameter than the arms 2 and 3 preventing such intimate contact of the arms as to preclude the placing of the hair between them. The curler however, is of such length that the arms 2 and 3 somewhat remote from the said enlargements 4 may be brought into parallel relation, and adjacent the point or bend 1 brought into intimate contact with each other to insure a more perfect grip upon

the hair and to aid in rolling the same without losing the gripping effect on the ends of the hair.

In employing the curler in the performance of its functions, a strand of hair is selected, such for example as the strand designated 5 in Figure 1. After this strand is separated from the remainder of the hair, the curler is brought into position wherein it will straddle the strand 5 after the manner shown in Figure 1 and it will be noted from this figure that the strand 5, selected, is of less width than the length of the arms 2 and 3, so that a fair portion of the length of the curler will extend beyond each side of the strand 5. The curler is positioned at substantially the end of the hair strand 5 and after being brought into this position, the opposite ends of the curler are grasped between the thumb and first finger of both hands of the operator and the arms 2 and 3 are forced tightly toward one another to tightly clamp the strand 5 between these arms. Because of this clamping action, we prefer to call the arms 2 and 3 clamping jaws as this better explains their function and mode of operation. After the clamping jaws 2 and 3 have been caused to tightly clamp the hair as described, a rolling movement is imparted to the curler, so that the curler is caused to rotate on its longitudinal axis, its operation being carried out while the clamping arms are maintained in the tight clamping relation described.

The rolling operation continues to the position of Figure 2 by which time the hair is wound tightly around the curler and further manual pressure to hold the jaws together will be unnecessary so that the rotating movement referred to may be continued until the hair is rolled up tightly to the scalp. The rolling operation is now concluded and it remains to lock the assembly against unrolling. This is done by bending the protruding ends of the curler over the hair roll after the manner shown in Figure 3, in which position the protruding ends of the curler become clamping members which tightly engage the hair roll and positively preclude its loosening. Hair pins or other expedients which are necessary in prior devices are not necessary with this invention and it is found in practice that the hair may be put up tightly and will remain tight even overnight and without the employment of any extraneous means such as hair pins. This is due to the double or triple clamping action referred to.

Inasmuch as there are no unprotected ends, the wearer of curlers embodying this invention is thoroughly safeguarded against injury from the wire core within the construction.

After the hair has been "up" as long as necessary, the curlers may be readily re-

moved by simply bending out the ends of the curler from the position shown in Figure 2 whereupon the coiled hair may be unwrapped and the curlers removed and 5 straightened out ready for the next use.

It will be noted that during any of these operations, there is no pulling of the hair nor catching of individual hairs or small strands in the curler as is the case in practically every curler now on the market. The 10 hair cannot catch in the curler of this invention for the reason that there are no constricted portions or no twists or projections.

Wire of the character described having a 15 fabric covering is very satisfactory for use in the manufacture of curlers embodying this invention inasmuch as the fabric surface of the curler is, in effect, a friction surface, inasmuch as it will frictionally engage 20 the hair when the jaws are brought into clamping relation so that the hair will not be apt to pull out from between said jaws. We therefore prefer to employ a fabric covered wire in the manufacture of curlers made 25 in accordance with this invention.

Aside from the foregoing uses of the curler, it may be stated that it may be employed to advantage in the making of ringlets and round marcel, experience having

proven that it is highly efficient for this purpose, whereas with other curlers on the market the hair is more or less frizzed and smooth curls are not possible. 30

The accompanying drawings illustrate the invention in its preferred form, but the 35 invention is to be construed as fully commensurate with the appended claim.

Having thus fully described the invention, what we claim as new and desire to secure by 40 Letters Patent is:

As an improved article of manufacture a hair curler formed of a single pliable covered spring wire bent intermediate its ends to form two spring clamping jaws normally 45 divergent from their bend and adapted to be manually forced together to grip hair therebetween, opposite ends of the curler being adapted to be bent towards each other and over the hair to clamp the hair rolled against loosening, the free ends of said clamping 50 jaws being provided with hardened globular protecting coverings constituting protuberances of greater cross section than that of said jaws.

In testimony whereof we have signed the 55 foregoing specification.

ROBERT SCHEANBLUM.
GRACE SCHEANBLUM.
